United States Patent

Des. 237,424
Patented Nov. 4, 1975

237,424

SHOE

Bernd Hannemann, Belcamp, Md., assignor to Bata Shoe Company, Inc., Belcamp, Md.

Filed May 17, 1974, Ser. No. 471,172

Term of patent 3½ years

Int. Cl. D2—04

U.S. Cl. D2—278

FIG. 1

FIG. 2

FIG. 3

FIG. 1 is a side-elevational view of the shoe embodying my design;

FIG. 2 is a front-elevational view of the shoe as seen in FIG. 1; and

FIG. 3 is a back-elevational view of the shoe.

The characteristic feature of my design resides in the foxing tape portion of the shoe design, all as shown in the drawings.

I claim:

The ornamental design for a shoe, substantially as shown and described.
